Patent expires March 9, 1965

5 Claims. (Cl. 235—144)

1

My invention relates to a zeroizing or clearing mechanism in a calculating machine comprising operatively interengageable totalizer dials for decimal transfer. When turning such a dial through an angle corresponding to an ordinal unit thereof, the adjacent dial of the next higher decimal order is turned through an angle which amounts to a fraction of the first angle. When, therefore, the first dial is turned through a full revolution, the second dial is turned through an angle corresponding to a unit of its own denomination.

In calculating machines of this class, a conventional zeroizing mechanism cannot be used for clearing the dials.

The dials of the zeroizing mechanism according to my present invention, now, are provided, apart from a collective clearing member, for example, a rack, with a restoring slide which is moved in dependency of the said member and which aids in zeroizing the dials.

Such provision permits of clearing a value registered in the accumulator of the machine, and to simultaneously transfer same into the key board setting mechanism or an auxiliary mechanism for temporary storage which, as known, in the art, is of great advantage.

One form of invention is shown in the drawings, by way of example, as applied to a calculating machine comprising parallel dial shafts. The drawings substantially are limited to the parts and portions requisite for explaining my invention, and in which:

Fig. 1 shows an elevation,

Fig. 2 a partial horizontal section of Fig. 1,

Fig. 3 a partial side view,

Fig. 4 two adjacent totalizer shafts in elevation, their appurtenant parts having been demounted therefrom,

Fig. 5 perspective a plurality of totalizer shafts with their appurtenant parts,

Fig. 6 perspective the restoring slide,

Fig. 7 in section, a totalizer shaft with gear parts including clearing rack and restoring slide,

Figs. 8-10 are views similar to Fig. 7, for explaining the operation of the elements shown,

Figs. 11-11a together show perspective parts and portions of the clearing mechanism and of a correcting device which serves to adjust the additionally turned dials into their correct ordinal position,

Fig. 12 shows a part of Fig. 11 in side view,

Fig. 13 a toothed slide and its actuating arm,

Fig. 14 a cam wheel provided for a control arm.

2

Fig. 15 is a plan view of portions of the correcting device, and

Fig. 16 is a perspective view showing parts in positions assumed after beginning an operation.

The accumulator carriage of a calculating machine equipped with stepped drums is provided (as disclosed in Swiss Patent No. 245,418 of H. W. Egli A. G.) with a rigid frame comprising, as shown in Fig. 1, two longitudinal horizontal main plates 1 and 2 rigidly interconnected by stay bolts 3, a bottom plate 5 being mounted to the lower main plate 1 by stay bolts 4 and a head plate 7 to the top main plate 2 by stay bolts 6. Five parallel totalizer shafts 8 are journaled in bottom plate 5 and head plate 7, and are provided at their foot end with a bevel gear 9 pinned thereto. Gear 9 cooperates with a pair of gears 10 (Fig. 3) which are pinned to a common hub. Thus a reversing spool gear of known type is afforded, operable by means of a control bar (not shown) to slide on the square shaft 11 so as to bring one or the other gear 10 into mesh with gear 9 of shaft 8, according to whether the latter is to be turned in the additive or subtractive sense. The square shafts 11 are rotated (in a manner known per se) by stepped drums (not shown). A dial 12 (Figs. 1, 5) is mounted to each shaft 8 and may be viewed through a window 13 provided in head plate 7. Dial 12 is pinned to the top end of a sleeve 14 (Figs. 3, 4) mounted on the respective shaft 8. Two toothed gear wheels 15 and 16 are pinned to the ends of sleeve 14, and a disc 17 to the bottom end thereof. Disc 17 is coupled to a spider 19 by means of a pin 18, spider 19 having a recess 20 (Fig. 9) for engaging pin 18. Toothed wheels 15 possess (according to Figs. 7-10) an interdigital gap intermediate of any 8 subsequent teeth. Recess 20 of spider 19 of shaft 8, being associated with a first calculating position, corresponds, according to Fig. 2, to the diameter of coupling pin 18. The appurtenant disc 17 has a circular periphery, whereas the other discs 17 have a notched periphery. Recess 20 of the spiders 19 associated with the remaining totalizer shafts 8, is so dimensioned as to permit of a predetermined relative rotation between disc 17 and spider 19; the castellated or notched discs 17 represent correction discs. A tension spring 21 biases pin 18 into abutment against one end of elongated recess 20 in the said spiders 19. An internal gear 22 is pinned to each spider 19 and meshes with two planet wheels 23 (Fig. 4) which are pivoted, diametrically opposite to each other, to a common mount 24.

which is fastly secured to the respective totalizer shaft 8. The planet wheels 23, on the other hand, enmesh with a sun wheel formed by a pinion 25 mounted on shaft 8. The sleeves 14 of adjacent shafts 8 are of different lengths so that a total of two groups of sleeves 14 are formed and, therefore, the correction discs 17 in the said frame are distributed in two planes, as are the internal gears 22 of the planet gears, in order to permit of placing shafts 8 as close as possible to each other. To such end the adjacent dials 12 also are superposed in two planes. The pinions 25 of the first, third and fifth ordinal columns thus are situated in the said frame on a lower level than the pinions 25 of the second and fourth ordinal columns. The pinions 25 of the second group are provided with a depending hub 26 (Fig. 4) which at its foot end has a gear 27 pinned thereto. Gears 27 are situated at one and the same elevation with the pinions 25 of the first group. A set collar 28 mounted on each shaft 8 permits of raising or lowering sleeve 14. Bevel gear 9 pinned to the foot end of shaft 8 is provided with a locking disc 30 secured to its hub 29. Disc 30 is circumferentially notched for positively engaging a leaf spring 31 (Fig. 5) secured to the underside of main plate 1, so as to maintain shaft 8 and, therefore, the corresponding dial 12 (by way of planet gears 25, 23, 22) in the correct indicating position.

An auxiliary shaft 32 (Figs. 3, 5) is associated with two adjacent totalizer shafts 8 each, parallel thereto, and a gear 33 pinned thereon meshes with gear 16 of sleeve 14 of an adjacent shaft 8. A pinion 34 is pinned to the foot end of auxiliary shaft 32, which latter is journaled in the main plates 1 and 2, and meshes with a gear 35 which is pivoted on a stud 36 (Fig. 5) secured to main plate 1 and is operatively connected with the pinion 25 of the shaft 8 belonging to the next higher ordinal column, either by direct engagement with the pinion 25 situated on the same level, or by way of gear 27 when the corresponding pinion 25 is situated on a higher level than the associated gear 33. Sleeves 14 of shafts 8, and thus the dials 12, are rotatably interconnected, such a driving ratio being provided that, when dial 12 of one ordinal column is rotated by one division or unit respectively, dial 12 of the next higher column is turned by one tenth of its own division (unit), even when a number (given by the calculation) is set at the same time, into such column by means of dial 12. Let us assume, number 385 has been transferred into the accumulator, dial 12 of the unit column then is in a position in which digit 5 appears fully in the respective window 13 of head plate 7. Dial 12 of the tens column has been rotated, additionally to its rotation from 0-8, by one half of a division, since dial 12 of the unit column has been rotated by five units. The central portion of the dial 12 associated with the tens column, therefore, becomes visible between the digits 8 and 9 in the corresponding window 13 of head plate 7. Dial 12 in the hundreds column has been turned from 0 to 3 and additionally, from the unit column by $\frac{5}{10}$ of a division and, from the tens column by $\frac{1}{10}$ of a division so that such dial 12 does not indicate (in the respective window 13 of head plate 7) the digit 3 as required by the number (385) essential for the calculation. In order to obtain the correct numerical indication, the dials 12 of the tens- and hundreds-columns have to

be turned back by the amount of the additional rotation mentioned. To such end, the said correction discs 17 are used, as well as their associated parts and portions which will be described below.

The numeral 37 in Fig. 11 designates the main shaft of the calculating machine, which is journaled in two rigidly interconnected side shields 38 and 39 which pass, with a stepped portion, underneath main plate 1, and shields 38 and 39 are at right angles to the latter. A cam disc 40 is pinned to main shaft 37 and cooperates with a bell crank 41 which is pivoted on a pin 42 fastly secured to shield 38. Bell crank 41 is biased by a tension spring 43 which engages the second arm thereof. The latter receives a rod 45 in a fork 44 below main plate 1. Rod 45 is supported at its ends in two levers 46 and 47 passing through openings in the bottom main plate 1. Levers 46 and 47 are fulcrumed on a bar 48, and thus an oscillating structure is formed. The latter is journaled in the bearing blocks 49 and 50 which are secured to main plate 1 and receive the bar 48. The said structure cooperates, by means of a second arm of lever 47, with a two-arm auxiliary lever 51 which to such end is provided with a skew face 52 at one end. Auxiliary lever 51 is pivoted on a stud 53 secured to main plate 1, and is adapted, at its second arm, as fork 54 which receives a pin 55 of a flat control bar 56. The latter has longitudinal slots 57 wherein pins 58 of correction levers 59 are engaged. A correction lever 59 is associated with each ordinal column, with the exception of the unit column, and is of angular shape (Fig. 5) and cooperates with the correction disc 17 provided on the respective totalizer shaft 8. Each of the four correction levers 59 shown, two of which are disposed below and two above control bar 56, is pivoted on a vertical pin 60 secured to main plate 1, and is biased by a spring 61 into abutment against the periphery of the respective correction disc 17. A spring 62 acts onto auxiliary lever 51 (Fig. 11a).

The correction gear described operates as follows:

According to the example assumed above, the number 385 has been transferred into the accumulator, the dials 12 of all ordinal columns, with the exception of the unit column, being not in their proper indicating position, as explained above, due to the additional rotation impressed thereon. The correction takes place automatically at the end of a calculating operation, i. e. during the last revolution of main shaft 37 which is rotated by means of crank 63 and handle 64 (clockwise in Fig. 11). Bell crank 41 thereby is rocked by cam disc 40 into a predetermined position, in which it is disengaged from recess 74 provided on disc 40 and locked by dog 70 mounted on shaft 68, the said dog cooperating with pin 71 on crank 41; see Fig. 16. During such rocking, structure 45-48 is rocked by bell crank 41 so that lever 47 turns auxiliary lever 51 over the latter's skew face 52 against the action of spring 62. Control bar 56 thus is displaced, in direction of the arrow shown in Fig. 11a, so far as to disengage the correction levers 59 coupled thereto from the notches of correction discs 17, and to release the latter for rotation. At the end of a revolution of main shaft 37, bell crank 41 again may be brought to cooperate with cam disc 40 or into engagement with recess 74 thereof respectively. Bell crank 41, however, remains locked in said position by dog 70, until handle 64 is drawn rearward by

spring 65, thus bringing pin 66 into the track of detent 67. Pin 66 then abuts against detent 67 and swings same backward against the action of spring 69, whereupon dog 70 trips bell crank 41, due to a corresponding rocking of shaft 68. Bell crank 41 then is tripped also, swings back under the influence of spring 43, and again is engaged in recess 74 of cam disc 40. When bell crank 41 swings back, it also swings back the structure 45-47, spring 62 biasing auxiliary lever 51 acting to restore control bar 56 so that the state of conditions according to Fig. 11 is re-established. Such restoration only will be brought about when the numerical value set into the calculating machine has been transferred into the accumulator, as otherwise, at each revolution of main shaft 37, bell crank 41 inadvertently would drop into recess 74 of cam disc 40 in the course of the calculating operation, either when multiplying or dividing.

When transferring the numerical value in question into the accumulator, dials 12 are set in the manner described, bell crank 41 of the correction gear being disengaged from cam disc 40. During the last revolution of main shaft 37, the correction gear again is brought into the state according to Fig. 11, the correction levers 59, being biased by the springs 61, being rocked with their cranked end against the correction disc 17 (Fig. 5), due to the restoration of control bar 56. When an indicating dial 12 is in correct indicating position as represented by its figure, the proper correcting lever 59, as a result of the pivoting action, comes to rest on a tip of the proper correcting disk 17; the units place has no correcting lever 59 assigned to it. The correcting disks 17 of the indicating disks 12 which have had imparted to them a rotational movement adapted to positively effect carrying over (transfer) of the tens units, assume a position in which the proper correcting lever 59 cooperates by means of its arcuate edge surface with a notch of the proper correcting disk 17. In this way the correcting levers 59 are swung by their retractile springs 61 to such an extent that they repose with their tips at the bottom of the proper notches when the correcting disks are suitably turned back, whereupon the indicating dials 12 assigned to the tens, hundreds, and higher calculating positions and which have been turned for the purpose of carrying the tens forward, will be in numerically correct indicating position or again in zero position, if, during the calculating procedure they were not turned at least one unit. The totalizer shafts 8 must remain unbiased by the said turning back of dials 12 and correction discs 17 respectively, in order to maintain the registered numerical value unchanged for an eventual extension of the calculating operation. To such end, the leaf springs 31 (Fig. 5) acting on the locking discs 30 are subjected to a higher stress than the springs 21 (Fig. 5) biasing the coupling pins 18 of the corrections discs 17. The coupling pins, by the springs 21, normally are held in abutment (in the sense of Fig. 2) against one end of recess 20 provided in spider 19. The said recesses 20 permit of effecting the idling run required for the said turning back of dials 12. Since during the calculating operation, dial 12 of the units column does not have to perform an additional rotation, pinion 25 associated with a planetary gear of this first column, is locked peripherally against rotation by a detent 78 (Fig. 1) secured to main plate 1.

For the purpose of zeroizing the numerical values transferred into the accumulator, gear 15

(Figs. 1, 5, 7-10) provided on sleeve 14 of each shaft 8, cooperates with a rack 80 longitudinally displaceable on the top main plate 2 in guide lugs 19. The toothing of clearing rack 80 is sectionalized, i. e. interrupted, at five points (or respectively on as many points as there are totalizer shafts 8) and the gears 15, in the inactive position of the correction and the zeroizing gear, have their interdental gaps opposite to the corresponding toothless section of clearing rack 80 (Fig. 7). The clearing gear, further, possesses a restoring slide, shown in Fig. 6, which is guided displaceable, on fixed threaded pins engaged in the two upper slots 81', by two brackets 82 and 83 fastly secured to main plate 2. Restoring slide 81, according to Fig. 1, is coupled at the right hand end to a detent arm 84 which is pivoted to a bracket 85 secured to head plate 7, and which serves for cooperating with a dog 86 secured to clearing rack 80. A spring 87 engages the left-hand end (as seen in Fig. 1) of restoring slide 81, and the latter on the bottom is guided displaceably, at the said end, on a fixed threaded pin which is engaged in a slot 81'' (Fig. 6). The said latter pin is mounted on a bracket 88, Fig. 1, fixedly secured to the lower main plate 1. Two square followers 89 are secured to restoring slide 81, in a lower and an upper plane each, each to cooperate with a stay pin 90 (Figs. 3, 7-10) secured to the internal gear 22 of the planetary gear disposed in the corresponding plane.

The spring 87, biasing restoring slide 81, tends to maintain the latter in such position that the said pins 90 may freely pass by the followers 89 of slide 81, when registering numerical values into the accumulator. The restoring slide 81, therefore, remains unbiased during such registry. Clearing rack 80, by a spring 91, normally is held in the inactive position, in which (as shown in Fig. 1a) it abuts, by means of a pin 80', against a stop 92 fixed to main plate 2. Clearing rack 80 at its other end is coupled to a two-arm intermediate lever 94 by means of a pin 93 (Fig. 11). Lever 94 is pivoted on a pin 95 to a bracket 96 fastly secured to main plate 1. The second arm of lever 94 is coupled by a pin 97, to a flat toothed bar 98 (also see Fig. 13), which is guided longitudinally displaceable on two fixed pins 100 by means of two slots 99. Pins 100, as shown in Fig. 12, are secured to brackets 101 provided on the underside of main plate 1.

According to Fig. 11, a key 102 is pivoted on a pin 103 fixed to the outside of the machine frame. Key 102 is formed as two-arm lever, and may cooperate, over its second arm, with the skew face 104 of a flat control slide 105 which is guided displaceable on the machine frame on two fixed pins 107 engaged in elongated slots 106. Slide 105, biased by a spring 108, engages the angular groove of a coupling portion 110 by means of a pin 109. Coupling portion 110 is mounted axially displaceable, but non-rotatable, on main shaft 37, and the second coupling portion, 111, is mounted on latter rotatable, but axially non-displaceable. Coupling portion 110 is provided with two diametrically opposite recesses 112 for receiving two followers 113 fixed to coupling portion 111, for the purpose of coupling the said two portions. A disc 114, one side of which is adapted as cam face for biasing the control arm 115, is fastly secured to coupling portion 111. Arm 115 is pinned to a shaft 116 which is journaled in two brackets 117 secured to shield 39. Another arm 118 is pinned to shaft 116 and biased by a spring 119 so as to

press arm 115 against disc 114. Lever 118 co-
operates with the teeth of bar 98.

The zeroizing or clearing operation is as fol-
lows:

Assuming digit 9 is set in the accumulator, and
shall be zeroized. Key 102 (Fig. 11) is depressed
so as to be raised off a fixed supporting pin 120,
and to longitudinally displace control slide 105,
in cooperation with skew face 104 of the latter and
against the action of spring 108, so far as to bring
coupling portion 110 into engagement with the
followers 113 of coupling portion 111, by means of
pin 109 of slide 105, and thus to render the cou-
pling 110, 111 operative. Zeroizing or clearing
then is effected, when turning main shaft 37
(either by crank 63 in direction of the arrow
shown in Fig. 11, or eventually by motor drive)
by means of disc 114 during a revolution thereof.
During a certain and comparatively short initial
rotation of main shaft 37, arm 115 (as shown in
Fig. 11) first is rocked to the right by disc 114 and
by means of delay step 121 (Fig. 14) only so far
that arm 118 moves bar 98 (by way of shaft 116)
for such a distance that the clearing rack 80 is
displaced from the inactive position (shown in
Fig. 7) in direction of the arrow by one step into
the position shown in Fig. 8. In the latter, a
tooth of clearing rack 80 is brought into engage-
ment with a corresponding terminal tooth of gear
15 associated with each sleeve 14. The latter
then cannot follow the tension of spring 21 which
engages spider 19, when correction disc 17—in ac-
cord with the explanation given below—is tripped
for rotation. In the inactive position of clearing
rack 80, the toothless sections thereof are op-
posite the toothless sections of gears 15, as shown
in Fig. 7.

The said rocking of arm 115 stops, in that the
latter is contacted by a plane face 122 provided
on disc 114 (Fig. 14) so that during the corre-
sponding further partial revolution of main shaft
37, clearing rack 80 remains in its given position.
At this time, the correction arms 59 are so rocked
by means of cam disc 40 (Fig. 11) through bell
crank 41 of the correction gear, oscillating struc-
ture 45—48, auxiliary lever 51 and rod 56, as to
trip the correction discs 17 for rotation.

Arm 115 then is swung further to the right
(with respect to Fig. 11), by the delay step 123
(Fig. 14) of disc 114, so that clearing rack 80 is
displaced by a further step against the action of
spring 91, i. e. to the left with respect to Figs. 5
and 11, and to the right with respect to Fig. 1. Pin
86 secured to clearing rack 80, then enters into
cooperation with arm 84 pivoted to head plate 7,
thus displacing restoring slide 81 against the ac-
tion of spring 87. During the aforesaid second
stepwise movement of the clearing rack 80 the
toothed crown of the sleeve 14 comes into the po-
sition shown in Fig. 9, that is, the correcting disk
17 and the proper indicating dial 12 are turned
back a slight amount less than nine figure divi-
sions; the missing amount results from the cir-
cumstance that the toothed sleeve 14 which
forms a rigid unit with the correcting disk 17 and
the indicating dial 12 and which sleeve is rotat-
ably journaled on the result shaft 8, is held back
by the retractile spring 21 attached to the pin 18
of the correcting disk 17. The respective terminal
tooth of gear 15, which last has come into engage-
ment with clearing rack 80, thus is held in abut-
ment against the teeth of clearing rack 80, in
the sense of Fig. 9. The respective totalizer shaft
8 has been left behind by a full ordinal division,
due to the braking action performed by leaf

75

spring 31 (Fig. 5) onto its locking disc 30 (dur-
ing the tension of spring 21) until the said pin
18 of disc 17 has reached, according to Fig. 9, the
second end of recess 20 in spider 19.

Clearing rack 80, upon its second step initiated
by the delay step 123 of disc 114, is displaced so
far that restoring slide 81 is moved by the pin 86
of the clearing rack, in cooperation with arm 84,
through such distance that pin 90 (secured to
spider 19) is taken along by the follower 89 of
slide 81 and, therefore, spider 19 is rotated to-
gether with gear 22. The operative state of Fig.
9 thus is replaced by that of Fig. 10, the said
shaft 8 having been turned back, as required, by
the full division which has been left behind up
to now. Clearing rack and restoring slide 81
now have performed their full stroke in the
said direction, whereby the dial 12 mounted on
the said shaft 8 has been turned back from 9 to 0,
i. e. into zero-position, and the respective bevel
gear 9 of the apurtenant reversing spool gear
10 has been turned back by 9 divisions. In this
manner, the numerical value present heretofore
in the accumulator, can be transferred into the
keyboard setting mechanism or into an auxiliary
gear. The coupling pin 18, at the transition of
the operative state from Fig. 9 to that of Fig. 10,
is moved away from one end of recess 20 in
spider 19, and abuts against the other end there-
of.

In the final phase of the revolution of main
shaft 37, clearing rack 80, under the influence of
spring 91, is returned into the initial or inactive
position respectively, taking along the restoring
slide 81.

The inventive mechanism, of course, also may
be applied to calculating machines which do not
operate according to the decimal system. In
such case, the driving or transmission ratio for
the planet gears 22-25 associated with the totali-
zer shafts 8 has to be selected such that, upon
rotating a shaft 8 through one unit, the shaft of
the next higher denominational order is rotated
through the requisite fraction of such unit in
order that—after a full revolution of the said
first shaft—the said second shaft has been ro-
tated through a unit of its own denominational
column. Further, my present invention is not
limited to calculating machines in which, as in
the example described, the zeroizing mechanism
possesses a rack as main element, which is com-
mon to all the dials, and in which the tens-trans-
fer is produced by planet gears. The inventive
zeroizing mechanism also may be used when dials
formed by rollers are disposed on a continuous
shaft, and when the clearing rack provided in
the example described, is replaced by segmental
clearing gear disposed on a shaft.

What I claim and desire to secure by Letters
60 Patent is:

1. Calculating machine provided with figure
carriage, the result mechanism of which is pro-
vided with parallel result shafts on each of which
a toothed sleeve is rotatably mounted which car-
ries an indicating dial and a correction disk, the
toothed sleeves being provided with mutual driv-
ing connections for positively effecting the tens
transfer by a partial "crawl carry" of the indicat-
ing dial, each correction disk having a correcting
lever and a coupling pin assigned to it, the latter
being intended for effecting the cooperation of
a toothed crown of one of the planetary gears as-
signed to the indicating dial with planetary
wheels carried by the result shafts and for ef-
fecting meshing with the pinions rotatably dis-

posed on the result shafts, the coupling pin being adapted to have a certain amount of play ("idling"), the said toothed sleeves having a common clearing rack, which has a stop for operating a restoring setting slide which is provided with stops for cooperating with coacting stops present on the aforesaid concentric toothed crowns of the planetary gears for the purpose of effecting the final return step of said indicating dials into zero position, a drive shaft being provided with two cam disks, one of said cam disks being operatively connected with said clearing rack for moving the same upon rotation of the drive shaft, and the other cam disk being operatively connected with a control bar for moving said correcting levers.

2. Calculating machine according to claim 1 and in which a clutch is provided on the drive shaft which is adapted to be engaged by means of a key for starting the movement of the restoring rack.

3. Calculating machine according to claim 1, and in which a clutch is provided on the drive shaft, said clutch being engageable by means of a key for starting the movement of the restoring bar.

4. Calculating machine according to claim 1, and in which a clutch is provided on the drive shaft, said clutch being engaged and disengaged by means of a key through intermediary of a spring-loaded operating slide so as, when engaged, to initiate the movement of the restoring bar.

5. In a calculating machine, a figure mechanism carriage with a result mechanism having result shafts disposed parallel to each other, a rotatable toothed sleeve on each shaft, an indicating dial carried by the sleeve, means for establishing mutual driving connection between the toothed sleeves of successive result shafts to positively effect the tens transfer by a partial crawl-carry procedure, said means including a planetary gear assigned to each indicating dial and having a central pinion rotatably mounted on

each shaft, an internal gear crown concentric with the pinion, and planet wheels meshing with said pinion and said gear crown, a lost motion connection between said gear crown and said toothed sleeve, spring means for holding said gear crown at one end of the lost motion movement, gear wheels for connecting said gear crown of one result shaft to the central pinion of the planetary gear of the result shaft of the next higher value position, a clearing rack common to all said toothed sleeves of the result shafts, a drive shaft for said clearing rack, a cam disc on the drive shaft, means operatively connecting said cam disc to the clearing rack, a dog on said clearing rack, a restoring slide coacting with said dog and provided with stops, said internal gear crowns of the planet gears having stay pins cooperating with said stops on the restoring slide, whereby upon rotation of the drive shaft said stops act on the stay pins of the gear crowns for turning the latter and effecting the final return step of said indicating dials into zero position.

HEINRICH SUTER.
